UNITED STATES PATENT OFFICE

JOHN H. MUNSON, OF LOS ANGELES, CALIFORNIA

DESIGN FOR A HUB CAP

Application filed September 12, 1929. Serial No. 32,729. Term of patent 14 years.

To all whom it may concern:

Be it known that I, JOHN H. MUNSON, a citizen of the United States, residing at Los Angeles, in the county of Los Angeles and State of California, have invented a certain new, original, and ornamental Design for Hub Cap, of which the following is a specification, reference being had to the accompanying drawings, in which—

Fig. 1 is a perspective view of the hub cap and Fig. 2 is a side view thereof with a portion broken away and in section to facilitate the il-

lustration of the design of the front end of the hub cap.

The hub cap is provided at its outer side with a colored reflecting lens.

I claim:

The ornamental design for a hub cap as shown and described.

In testimony whereof, I have hereunto set my hand at Los Angeles, California, this 6th day of September, 1929.

JOHN H. MUNSON.
